HENRY DE SMITH, OF ROCHESTER, NEW YORK, ASSIGNOR TO M. D. KNOWLTON COMPANY, OF ROCHESTER, NEW YORK, A CORPORATION OF NEW YORK.

MACHINE FOR APPLYING BOX-CORNER STAYS.

1,160,390.

Specification of Letters Patent.

Patented Nov. 16, 1915.

Application filed December 20, 1909. Serial No. 534,108.

To all whom it may concern:

Be it known that I, HENRY DE SMITH, a citizen of the United States, and resident of Rochester, in the county of Monroe and 5 State of New York, have invented certain new and useful Improvements in Machines for Applying Box-Corner Stays, of which the following is a specification.

This invention relates to that class of machines adapted for applying stays or reinforcing strips to the corner joints of boxes or other receptacles made of paper-board or like material, and in which are embodied stay-strip applying means and stay-strip 10 feeding-means; the said feeding means being operative to feed a continuous stay-strip from a supply roll to said applying means to be acted upon thereby in usual and well-known manner.

20 The present invention relates particularly to improvements in the stay-strip feeding mechanism of such class of machines, and has for its main object the provision of a feeding mechanism that will be so constructed and organized as to permit of the 25 machine as a whole being made smaller and more compact in form than heretofore, and that will also be capable of effective operation under all conditions of work without 30 liability of undue strain or wear on the working parts thereof. This object is attained by means of the novel features of construction and combinations of parts hereinafter described and claimed.

35 Referring now to the accompanying drawings forming part of this specification,

Figure 1 is a side elevation, partly in section, of a machine embodying my invention. Fig. 2 is a front elevation of the 40 machine. Fig. 3 is a sectional detail showing the yieldable connection between two levers of the stay-strip feeding mechanism.

Similar reference characters designate 45 like parts in the several figures of the drawings.

As shown in said drawings, the main frame of the machine is formed by an integral casting embodying a horizontal bed-plate 1, a vertical standard 2 at one end of 50 said bed-plate, a horizontal arm 3 at the upper end of said standard overlying the bed-plate 1, and a vertical web 4 connecting at its margin with the said bed-plate, the standard and overlying arm. This frame,

upon which the several operative parts of 55 the machine are mounted, is supported at the proper height upon a suitable sub-frame or support 5, a portion only of which is shown in the drawings.

The stay-applying means of this machine 60 is substantially the same as that of other machines of the same class and includes two coöperating presser dies, one of which is normally stationary and the other reciprocatory. The stationary die, which is also 65 termed an anvil, is indicated at 6. This die is in the form of an elongated bar arranged horizontally and supported in the standard 2 somewhat above the bed-plate 1 with its front end extending beyond the face side of 70 the standard to support the boxes or other work thereon. The said die or anvil 6 is fitted to slide longitudinally in its seat or bearing in the supporting frame so that its front end portion may be extended a 75 greater or less distance from the face of the standard 2 according to the depth of the box to be stayed. Said die or anvil may be secured in its adjusted position by any suitable means, the means herein shown for such 80 purpose comprising a clamp-bar 7 resting at one end on a riser 8 on the bed-plate and at its other end resting on the upper flattened portion of the rear end of the anvil and being adapted to be held in clamp- 85 ing engagement with said anvil by means of a clamp-screw 9. The other or reciprocatory die, indicated at 10, is located at the front side of the standard 2 for co-operation with the upper face of the projecting front end of the lower die or anvil 6, and is suitably attached to a vertically 90 acting slide or plunger 11 which is operative in guides 12, 12, at the face side of the standard 2 and connected through the 95 medium of a suitably constructed pitman 13 with an actuating part, here shown as a crank-pin 14 carried at the front end of a driving shaft 15 mounted in the upper horizontal arm 3 of the supporting frame; said 100 shaft being adapted to be connected with or disconnected from a driving pulley 16 through the medium of a suitable clutch (not shown) for the purpose of controlling the action of the die 10 and associated working parts.

In the operation of the machine, as hereinbefore referred to, the stay-strip, indicated

by dotted lines at *s*, is fed by a suitable feeding mechanism from the supporting reel *r* to a position between the dies 6—10 and over the corner of a box supported on the lower die; following which, a downward movement of the plunger 11 first causes a cutter 17 carried thereby to sever the stay to be applied to the box from the continuous strip, and thereafter causes the die 10 also carried thereby to apply the severed stay to the box corner by coöperation with the lower die, in usual and well-known manner. I will now describe the construction and operation of the said stay-feeding mechanism. This feeding mechanism comprises a reciprocating strip-engaging device together with means for operating said device in a manner whereby it will be caused to engage and carry forward the strip in its forward feeding movement and then become released from the strip at the limit of its forward movement so as to move backwardly without producing any corresponding movement of the strip. Said strip-engaging device itself is of substantially usual and well-known construction and comprises a plate 18 slidably connected with a stationary guide-plate 19 and having connected therewith two co-operating gripping jaws arranged to permit of the passage of the stay-strip therebetween; one of said jaws, indicated at 20, being fixed with respect to the plate 18 and located in position for engagement with the stay-strip at the under side thereof, and the other jaw, indicated at 21, being pivoted to the plate 18 and located in position for engagement with the strip at the upper side thereof. With this construction of device, the movable or pivoted jaw 21 should be caused to coöperate with the jaw 20 to engage and carry forward the strip upon the forward movement of the device, and to release the strip at the limit of the forward movement of the device and maintain such release during the return movement of the device. Such operation of the strip-engaging device is effected in the present case and in accordance with my invention by suitable means operated from the vertically acting plunger 11 of the strip-applying means. These means for operating the strip-engaging device from the plunger 11 may be of any suitable construction capable of performing the required functions, the same in the present case including a series of operatively connected levers, indicated at 23, 24, and 25; the lever 23 being mounted on a pivot-pin 26 on the frame with one end having operative connection with the plunger 11 by means of an anti-friction roll 27 on said lever engaging the plunger within a seat 28 therein, and the levers 24 and 25 both being mounted on a second pivot-pin 28' on the frame and both being operatively connected for movement in unison, with the

lever 24 having operative connection with the lever 23 by means of an anti-friction roll 29 on one lever engaging the other lever within an elongated slot 30 therein, and with the lever 25 having operative connection through a link 31 with a lever-arm 21' of the movable or pivoted gripping jaw 21 of the strip-engaging device. With this described combination of parts, the said levers are rocked on their pivots upon the vertical movement of the plunger 11 and thereby caused to operate said movable jaw 21 of the strip-engaging device in usual manner, that is, upon the forward throw of the lever 25 the said device is given a corresponding forward movement with the jaw 21 in gripping engagement with the strip and upon the backward or return throw of the lever 25 the said device is given a corresponding backward movement with the jaw 21 raised and released from engagement with the strip.

As well known by those familiar with the art, the length of stay fed between the dies 6—10 should vary according to the depth of the box to be stayed, and this is arranged for by the provision of means for regulating the length of the feed stroke or movement of the strip-engaging device. In the present case two stops are provided for engagement with the feed lever 25 to regulate the extent of its movement and thereby that of the connected strip-engaging device; one of the stops, indicated at 32, limiting the forward movement of the lever and the other stop, indicated at 33, limiting the backward movement of the lever. The stop 33 is shown as being formed at the upper end of a lever 34 which is pivoted to the web 4 of the supporting frame at 35 with its lower end having a slot-and-pin connection 36 with the rear end of the die or anvil 6. With this connection of the stop-lever 34 with the anvil 6, forward or backward adjustment of the latter to accommodate different depths of boxes also operates to shift the position of the connected stop 33 and thereby effect a corresponding adjustment in the extent of movement of the lever 25 and connected strip-engaging device, whereby different lengths of stay will be fed to correspond to different depths of boxes.

In view of the fact that the plunger 11 has a substantially fixed or predetermined length of stroke, while that of the strip-engaging device is adjustable, it will be understood that the connections between the said plunger and the strip-engaging device should be sufficiently yieldable to permit of any difference in the relative movements of said parts. For instance, the movement of the levers 23 and 24 as imparted thereto from the plunger 11 is sufficient to impart a maximum length of feed stroke to the strip-engaging device, but in case the stop 33 is set to cause a shorter length of feed stroke

to said strip-engaging device, the feed lever 25 will be engaged by the stop 33 and its movement be limited thereby prior to the limit of upward movement of the plunger. 5 To provide for this and permit of the full movement of the plunger without breakage or other damage to the connecting parts, the connection between the levers 24 and 25 is a yieldable one and is provided as follows: At 10 their point of connection with the pivot-pin 28', the said levers 24 and 25 are frictionally clutched or connected, preferably with their adjacent faces in contact with an interposed friction washer 37 of leather or other 15 suitable material, in a manner whereby they will be caused to normally move in unison during the movement of the plunger and strip-engaging device, but be capable of movement relative to each other upon the 20 stopping of one of said parts prior to the other, as referred to.

Any suitable means may be employed for effecting the described frictional connection of the levers 24 and 25. The means employed in the present case, as most clearly shown in Fig. 3, comprise an end-thrust ball-bearing 38 at the inner end of the pivot-pin 28' to receive the contact of the adjacent lever 25, and an adjustable nut 38' threaded 25 onto the outer end of the pivot-pin 28' and acting against the adjacent lever 24 through a spring 39 to maintain the desired frictional connection of said levers.

Upon the forward or feeding movement of 30 the lever 25 and connected strip-engaging device, the said lever is brought into engagement with the forward stop 32 prior to the limit of the down stroke of the plunger for operating the connected cutting and clamping devices. This difference in movement of the parts, however, is also provided for by the described yieldable connection between the levers 24 and 25.

Having now illustrated and described one 35 practical embodiment of my invention, I wish it to be understood that I do not limit myself to the particular embodiment of the invention so illustrated and described, as the same may be more or less materially modified without departure from the spirit of my invention as called for in the following claims.

What I claim is:

1. In a machine for applying fastening 40 stays, the combination with stay-strip applying means including a reciprocating pressing member, of a feeding mechanism for imparting intermittent feeding movement to a continuous stay-strip and including a reciprocating slide having a pair of strip-engaging jaws mounted thereon between which the stay-strip passes and one of which jaws is pivoted, and connections from 45 said reciprocating pressing member to said pivoted jaw operative to rock the latter to

and from strip-engaging position and also to impart reciprocating movement to the jaw-supporting slide.

2. In a machine for applying fastening stays, the combination with stay-strip applying means including a reciprocating pressing member, of a feeding mechanism for imparting intermittent feeding movement to a continuous stay-strip and including a reciprocating slide having a pair of strip-engaging jaws mounted thereon between which the stay-strip passes and one of which jaws is pivoted, adjusting means for varying the working stroke of said jaw-supporting slide, and yieldable connections from said reciprocating pressing member to said pivoted jaw operative to rock the latter to and from strip-engaging position and also to impart reciprocating movement to the jaw-supporting slide.

3. In a machine for applying fastening stays, the combination with stay-strip applying means including a reciprocating pressing member, of a stay-strip feeding mechanism including a pair of jaws between 90 which the stay-strip passes and one of which jaws is pivoted, a system of levers connecting said pivoted jaw to said reciprocating pressing member whereby the jaw is brought into positive engagement with the stay-strip 95 prior to the feeding movement of the jaws, a yielding connection between said levers, and an adjustable stop arranged in the path of one of said levers to limit the feeding movement of the same.

4. In a machine for applying fastening stays, the combination with stay-strip applying means including a reciprocating pressing member, of a stay-strip feeding mechanism including a pair of jaws between which 100 the stay-strip passes and one of which jaws is pivoted, a rocking lever connected at one end to said reciprocating pressing member, a pivot pin, a pair of levers mounted on said pivot pin and extending in different directions therefrom, one of said pair of levers having connection with said rocking lever and the other having operative connection with the said pivoted jaw of the feeding mechanism, a friction member interposed between the adjacent ends of said pair of levers at their point of support upon the pivot pin, and a tension spring carried on said pivot pin for yieldingly binding said pair of levers together for movement in 110 unison.

5. In a machine for applying fastening stays, the combination with stay-strip applying means including a reciprocating pressing member, of a feeding mechanism for imparting intermittent feeding movement to a continuous stay-strip and including a reciprocating strip-engaging device mounted independently of said pressing member, means for limiting the movement of said 120 125 130

strip-engaging device in advance of the limit of movement of said reciprocating pressing member, and yieldable means embodying two frictionally-connected parts for imparting feeding movement to said strip-engaging device from said reciprocating pressing member.

Copies of this patent may be obtained for five cents each, by addressing the "Commissioner of Patents, Washington, D. C."

Signed at Rochester, in the county of Monroe, and State of New York, this 7th day of December, A. D. 1909.

HENRY DE SMITH.
